UNITED STATES PATENT OFFICE.

WILLIAM C. KORZINEK, OF WEEHAWKEN HEIGHTS, NEW JERSEY, ASSIGNOR TO
PACIFIC MILLS, OF BOSTON, MASSACHUSETTS, A CORPORATION OF MASSACHU-
SETTS.

DESIGN FOR TEXTILE FABRIC OR WALL-PAPER.

42,851.

Specification for Design.

Patented Aug. 6, 1912.

Application filed May 29, 1912. Serial No. 700,529. Term of patent 3½ years.

To all whom it may concern:

Be it known that I, WILLIAM C. KORZINEK, a citizen of the United States, residing at No. 474 Gregory avenue, Weehawken Heights, in the county of Hudson and State of New Jersey, have invented a new, original, and ornamental Design for Textile Fabrics or Wall-Papers, of which the following is a specification, reference being had to the accompanying drawing, forming part thereof.

The drawing is a plan view of a portion of a textile fabric or wall paper showing my design.

I claim:

The ornamental design for a textile fabric or wall paper as shown.

WILLIAM C. KORZINEK.

Witnesses:

PHILIP F. WICKSEL,
WILLIAM I. MEEHAN.
